SEWING MACHINE

Carl A. O. Grip, Newton, Mass., assignor to The
Reece Button Hole Machine Company, Bos-
ton, Mass., a corporation of Maine

Application December 5, 1938, Serial No. 243,968

2 Claims. (Cl. 112—76)

This invention relates to buttonhole and similar sewing machines, and more particularly to the work holding and clamping mechanism employed in such machines, and is in the nature of an improvement on the work clamping mechanism covered by an application filed December 1, 1938, by Joseph H. Pikul, Serial No. 243,311.

In said Pikul application is described a simplified work clamping mechanism wherein, as distinguished from mechanisms heretofore employed for this general purpose, the fabric is tightly and securely held at substantially all points surrounding the stitching area (i. e., the region in which the buttonhole or similar stitches are located), is evenly stretched or tensioned in all directions, and is properly positioned for the action thereon of the stitching and cutting instrumentalities. Said mechanism comprises a unitary work plate having an opening therethrough and a single complementary work clamping member adapted to enter said opening, clamp the interposed fabric between itself and the peripheral edge of the latter, and deflect or depress the portion of the fabric within said edge into a position with its bottom surface substantially flush with the bottom surface of the work plate, thereby tensioning the same and positioning it for the action of the stitching and cutting instrumentalities, said clamping member having an opening therethrough of such size and shape as to expose and enclose the stitching area and through which the stitching and cutting instrumentalities operate upon the depressed and tensioned portion of the fabric.

The mechanism of said application is eminent-
ly suitable and satisfactory for use in connection
with relatively heavy, stiff, and inelastic or non-
stretchable materials, such as leather and certain
kinds of woven fabrics, but it has been found
that, when operating upon relatively light, soft,
and highly stretchable goods, such, for example,
as knitted fabrics, the proper tensioning of the
material requires a greater stretching thereof
than is practicable with said mechanism as dis-
closed in said application, and also that it is
desirable to make some provision for insuring the
proper and even engagement of the clamping
member with the work in order to prevent dis-
placement or distortion of the latter. The pres-
ent invention has for its object to provide a
mechanism of this type which will satisfy these
requirements. To this end, while retaining the
unitary work plate and single cooperating clamp-
ing member of said application, with their ad-
vantages, the present invention contemplates the

provision of a clamping member comprising two
relatively movable portions adapted respectively
to clamp and securely hold the work about the
edge of the opening in the work plate and there-
after to deflect, stretch, tension, and position the
same. The invention also includes improved
means for mounting the clamping member upon
its carrier to cause its clamping portion to en-
gage the work in a position substantially parallel
to the latter irrespective of the thickness there-
of, while permitting said portion to adapt itself
to irregularities in the work and to maintain its
position of engagement during the subsequent
stretching operation.

The foregoing and other objects of the invention,
together with means whereby the latter may
be carried into effect, will best be understood
from the following description of an illustrative
embodiment thereof shown in the accompanying
drawings, this, however, having been chosen for
purposes of exemplification merely, as it will be
obvious to those skilled in the art that the invention,
as defined by the claims hereunto appended,
may be otherwise embodied without departing
from its spirit and scope.

In said drawings:

Fig. 1 is a side elevation, partly in section, of
a machine including work clamping mechanism
embodimenting the invention.

Fig. 2 is a plan view, partly broken away, of
the work clamping mechanism per se and asso-
ciated parts.

Fig. 3 is a section taken substantially on the
line 3—3, Fig. 2 showing the parts in a different
position.

Figs. 4 and 5 are views similar to Fig. 3 show-
ing the parts in different positions.

Fig. 6 is an enlarged section taken substantially
on the line 6—6, Fig. 3.

Fig. 7 is a section taken substantially on the 40
line 7—7, Fig. 6.

Referring to Fig. 1, the invention is shown as
applied to a buttonhole or similar machine of a
well known type comprising a stationary bed
frame 15 carrying the work clamping mechanism,
hereinafter described, and a movable stitch frame
or head 16 carrying the stitching mechanism as
well as cutting mechanism for cutting the but-
tonhole or the like. The stitch frame 16 is mov-
able longitudinally over the bed frame 15 to 50
bring the stitching and cutting mechanisms al-
ternatively into operative relationship with the
work, and also longitudinally or laterally or both
to position the stitches in accordance with the
work to be performed, by means of mechanism 55

operated by a main cam 17 carried by the stitch frame 16 and rotated by a feed shaft 18 likewise carried by said frame. This mechanism is well known in the art, being shown, for example, by the patents to Reece, No. 240,546, April 26, 1881, and No. 655,637, August 7, 1900, and many others, and requires no detailed description herein.

The stitching mechanism comprises a needle 19 carried by a needle bar 20, and looper mechanism 14 which may be substantially as shown in the patent to Grip, No. 1,905,854, April 25, 1933, said needle bar and looper mechanism being carried respectively by upper and lower turrets 21 and 22 rotated in unison at the proper time by gear segments 23 and 24 carried by a rock shaft 25 operated by the main cam 17 as further described in the Reece patents above referred to. The lower turret 22 also carries a throat plate 26 through which the needle 19 passes to cooperate with the looper mechanism. The needle bar 20 is reciprocated vertically and vibrated laterally in its turret 21 from suitable cams on a stitching shaft 27 through mechanisms generally indicated at 28 and 28a, respectively, and which may be substantially as shown and described in the patent to Reece, No. 1,991,627, February 19, 1935. The looper mechanism carried by the turret 22 is likewise operated from the stitching shaft 27 by mechanism generally indicated at 29 and which may be substantially as shown and described in the patent to Grip above referred to and in the patent to Dunnell, No. 1,935,083, November 14, 1933.

The cutting mechanism comprises upper and lower cooperating cutting elements 30 and 31, the former of which is carried by a lever or arm 32 operated at the proper time from the main cam 17, as described more fully in the patent to Kiewicz, No. 1,841,133, January 12, 1932.

The work clamping mechanism, hereinafter more fully described, and which, as above stated, is carried by the bed frame 15, includes a work or clamp plate 33 and cooperating clamping means carried by a pair of arms 34 pivoted at 35 to said work plate and operated by mechanism including a swinging frame or rocker 36, toggle 37 and lever 38 which in turn is operated by the cam 17, the latter mechanism, as herein shown, being substantially as more fully described in the Kiewicz patent above referred to and in the patent to Hill, No. 713,764, November 18, 1902.

It will be understood that, in machines of this character, suitable mechanism is provided whereby the machine, when started, will perform its operative cycle and then automatically stop, said cycle including, first, a closing of the work clamp to clamp the work, then a movement of the stitch frame from a cutting position in which the cutting elements are adjacent the stitching area, into a stitching position in which the stitching instrumentalities are adjacent said area, a stitching operation of a character determined by the design of the feed mechanism, a return of the parts into cutting position, and, finally, the opening of the work clamp to release the work, said cycle also including a cutting operation which may be performed either before or after the stitching operation according to the design or adjustment of the machine.

Except as hereinafter pointed out, or as they enter into combination with parts hereinafter described, the mechanisms above referred to specifically form no part of the present invention and may be as shown and described in the pat-

ents referred to, or otherwise, as will be well understood by those skilled in the art.

As in the Pukul application above referred to, the work plate 33 comprises a single, functionally unitary member removably positioned on the bed frame 15 by lugs or dowels 39 projecting upwardly from the latter and received in openings 40 in said work plate. Adjustably secured, as by screws 41, to the rear or inner end of the work plate are lugs 42 to which the arms 34 are pivoted, said plate having slots 43 through which the lower ends of said arms project for detachable connection with the rocker 36, permitting removal of said arms with the work plate. At its underside, the work plate 33 is grooved, as shown at 44, to receive the throat plate 26 and lower cutting element 31 and permit movement of said plate and element alternatively into operative position, the portion of said plate above said groove being, however, of substantial thickness, and its bottom surface being substantially flush with the tops of said plate and element, except for the necessary clearance. The portion of the work plate 33 last referred to is provided with an opening 45 therethrough, said opening being preferably, and for convenience, formed in a removable portion or slide 46 which, however, is normally stationary with respect to the plate so as, in operation, to constitute a unitary part thereof, being secured in this position by a spring pressed latch 47 as shown in Fig. 2. Cooperating with the work plate 33 is a single clamping member 48 carried by and between the arms 34.

In accordance with the present invention, the clamping member 48 comprises a head 49 pivoted at 50 to the arms 34 and comprising a tubular portion 51 and a separate work clamping portion or element 52.

The tubular portion 51, which is adapted, when the clamping member is depressed, to enter the opening 45 in the work plate 33, and through which the stitching and cutting instrumentalities operate, may be formed integral with the head 49 or may comprise a separate sleeve permanently secured, as by brazing, to said head. It is of such size and shape as to enclose the stitching area and to receive within the confines of its inner periphery all of the stitches positioned by the feeding movements of the stitch head and the rotation of the turrets in accordance with the character of the work to be performed. The particular machine herein shown is arranged to sew oval buttonholes disposed parallel with the edge of the goods, the stitch feeding movement of the stitch head being entirely or chiefly in a direction transverse to the machine, and the tubular member 51 is accordingly of approximately oval shape with its longest dimension transverse to the machine, as is also the opening 45 which, while slightly larger in size, corresponds generally in shape with said tubular member. To the same end, the lower cutting element 31 comprises a transversely disposed knife to cooperate with a transversely disposed cutting block or anvil 30 carried by the lever 32. It will, of course, be understood that, for sewing buttonholes or the like of other forms, work plates (or slides 46) and clamping members having, respectively, openings 45 and tubular portions 51 of appropriate shapes, as well as suitable cutting elements, can be substituted for those shown.

The work clamping portion or element 52 comprises a substantially flat plate surrounding and guided on the tubular portion 51 of the head, and corresponding thereto in shape, so as to be

adapted to engage and clamp the work *W* upon the surface of the work plate and about the edge of the opening *45* substantially continuously throughout a region completely surrounding the stitching area. The clamping element *52* is carried by headed plungers *53* guided in the head *49*, said element being normally held in the position shown in Figs. 3, 4 and 6 by springs *54* surrounding said plungers and interposed between 5 said element and the inner ends of recesses formed in the said head. The springs *54* are of sufficient strength to exert an adequate clamping pressure upon said clamping element.

The work *W* having been positioned on the 15 work plate *33*, with the clamping member *48* elevated as shown in Fig. 3, the clamp operating mechanism is operated to depress said clamping member to bring the clamping element *52* into engagement with the work, as shown in Fig. 4, 20 thereby firmly clamping said work to the upper face of the work plate about the opening *45* in the latter. Continued downward movement of the head *49* causes the tubular portion *51* thereof, operating through the clamping element *52*, to 25 enter the opening *45* (the springs *54* yielding for this purpose), ultimately depressing said work into said opening into a position with its bottom surface substantially flush with the bottom surface of the work plate and therefore with the 30 tops of the throat plate *26* and cutting element *31*, as shown in Figs. 1 and 5. Consequently, the movements of the throat plate and cutting element into and out of operative position, i. e., into and out of register with the opening *45*, need 35 be only in a plane parallel with the work plate, said members, however, being in close proximity to the work when brought into operative position. This subsequent downward movement of the tubular portion *51*, after the work has been 40 firmly clamped by the clamping element *52*, acts to stretch the work across the open lower end of said tubular member like a drum head, thereby adequately tensioning the same in all directions.

The pivotal mounting *50* of the clamping member *48* on the arms *34* permits the clamping element *52* to engage the upper surface of the work evenly notwithstanding the arcuate movement of the ends of the arms by which the clamping member is carried, and in order to insure such even engagement, means are preferably provided for yieldingly fixing the angular position of the clamping member on its pivot, so

as to cause the element *52* to occupy a position parallel to the work plate at the time of its engagement with work of average thickness. As shown, such means comprises spring pressed plungers *55* guided in enlarged portions *56* of the arms *34* and engaging the head *49* at opposite sides, respectively, of the axis of the pivots *50*. The plungers *55* are backed by springs *57* which may be adjustably tensioned by abutment screws *58*, thereby balancing the pressures exerted by such springs in such a way as to determine the angular position of the head *49* about its pivots. The clamping element *52* is thereby caused to engage the upper surface of the work evenly at all points about the stitching area, but the springs *57* are capable of yielding to permit said clamping element to accommodate itself to variations in thickness of, and irregularities in the work, as where the latter is of greater thickness at one side of the buttonhole than the other, and also to compensate for the slight additional angular movement incidental to the final depression of the tubular portion *51* into the opening *45* to stretch, tension and position that portion of the work which is to be operated upon.

I claim:

1. In a sewing machine having stitching mechanism, work clamping means comprising a work plate and a clamping member having alined openings through which the stitching mechanism operates, said member comprising a portion adapted to clamp the work about the opening in said work plate and a portion adapted to depress the work into said opening, a carrier upon which said member is movably mounted, and means for yieldingly positioning said member on said carrier to cause the work clamping portion thereof to engage the work substantially parallel to said work plate.

2. In a sewing machine having stitching mechanism, work clamping means comprising a work plate and a clamping member having alined openings through which the stitching mechanism operates, a pair of arms having alined pivots by which said member is carried at opposite sides, and adjustable spring pressure devices carried by said arms and engaging said member at opposite sides of the axis of said pivots for normally maintaining said member in a predetermined angular position with respect to said axis.

CARL A. O. GRIP.
